UNITED STATES PATENT OFFICE.

GEORGE CASKEY, OF PAGE, IOWA.

DUMPING WAGON-BOX.

SPECIFICATION forming part of Letters Patent No. 616,897, dated January 3, 1899.

Application filed June 27, 1898. Serial No. 684,630. (No model.)

To all whom it may concern:

Be it known that I, GEORGE CASKEY, a citizen of the United States, residing at Page, in the county of Page and State of Iowa, have invented a new and useful Dumping Wagon-Box, of which the following is a specification.

The object of this invention is to provide improved means for dumping the contents of a wagon-box.

10 My invention consists in the construction, arrangement, and combination of elements hereinafter set forth, pointed out in my claims, and illustrated by the accompanying drawings, in which—

15 Figure 1 is a vertical longitudinal section of the device mounted on a wagon, the dotted lines indicating the opening of the device for dumping the contents of the box. Fig. 2 is a plan showing a pair of dumping-boxes placed 20 end to end on a wheeled truck or wagon.

In the construction and operation of the device as shown the numeral 10 designates 25 a supporting-frame, 11 12 front and rear axles on which the frame 10 is mounted, and 13 14 front and rear supporting-wheels for the axles.

The axles and supporting-wheels may be of an ordinary wagon from which the bolsters are removed, the frame 10 taking the place of the bolsters and reach and connecting the axles.

30 A dumping-box is mounted on the frame 10, and comprises end-boards 15 16, side-boards 17, (one only of which is shown in Fig. 1,) and a bottom formed in two sections 18 19. The

35 end and side boards are connected at their ends to form a box-frame, and the sections of the bottom are hinged to the lower edges of the end-boards and normally are held horizontally between the side-boards. A cross-bar 20 is fixed to the inner end portion of the section 18 of the bottom and projects downwardly from the lower face thereof. Hooks

21 (one only of which is shown in Fig. 1) are positioned vertically in and project at their upper ends from the end portions of the cross-

40 bar 20 through the inner end of the section 18 of the bottom adjacent to the inner faces of the side-boards 17. The hooks 21 turn forwardly of the box and are engaged by one end, respectively, of each of a pair of bell-

45 cranks 22 23, (one only of which is shown in Fig. 1,) fulcrumed on the inner faces of the side-boards 17 and held normally in horizon-

tal positions by retractile coil-springs 24, connecting the forward ends thereof with the side-boards, and stops 25 seated in the side-boards below the bell-cranks and limiting and determining the movement thereof by the springs. A chain 26 is connected at either end to the forward ends of the bell-cranks and has its bight run through screw-eyes 27 60 28 in the upper portions of the side-boards, and thence across the box between the screw-eyes. Longitudinal rods 29 are fixed to and extend horizontally rearwardly from the cross-bar 20 beneath the bottom. The rear 65 ends of the rods 29 pass through hangers 30, and the extremities thereof are curved downwardly. The hangers 30 depend from the inner edge of the section 19 of the bottom and are provided with rollers or sheaves 31 70 above and to be engaged by the rods 29. Two of the rods 29 and two of the hangers 30 are provided, one of each at each end of the cross-bar 20, although one of each only is shown in Fig. 1 of the drawings. Plates 32,33,34, and 35 75 are mounted vertically in the corners of the box and fixed to the inner faces of the side-boards thereof, the upper ends of which plates are apertured to admit hooks or bails (not shown) whereby the box may be attached to 80 a lifting apparatus and elevated for deposition of the contents thereof in a crib or other receptacle. (Not shown.)

In Fig. 2 of the drawings I have shown two of the dumping-boxes mounted on the supporting-frame. These boxes are not connected in any way and may be lifted and dumped or simply dumped independently of each other.

Portions of the bell-cranks are covered by sheet-metal shields 36, mounted on the side-boards to prevent packing of the grain in the box around and against the mechanism.

I claim as my invention—

1. The combination with a box the bottom of which is constructed of two hinged sections 95 meeting in the central portion of the box, of a cross-bar on one bottom-section, rods on the cross-bar, hangers on the other bottom-section receiving the rods, sheaves on the hangers to engage the rods, hooks on the cross-bar, bell-cranks on the side-boards of the box engaging the hooks normally and means for tripping the bell-cranks.

2. The axles and supporting-wheels, the sup-

porting-frame on the axles, the box on the frame and a bottom hinged in the box and arranged for dumping, in combination with a pair of rods on one section of the bottom, 5 hangers on the other section of the bottom arranged to receive the rods, a hook on the bottom and a tripable lever on the side of the box to receive the hook.

3. The combination with a box the bottom of 10 which is constructed of two hinged sections meeting in the central portion of the box, of rods on one bottom-section, a cross-bar fixed

to one bottom-section at right angles to the rods, hangers on the other bottom-section receiving the rods, hooks on the cross-bar, bell- 15 cranks on the side-boards of the box engaging the hooks normally, housings for the bell-cranks and hooks, and means for tripping the bell-cranks.

GEORGE CASKEY.

In presence of—
W. K. GLASGOW,
I. B. CASKEY.
